CIGAR BUNCH TRIMMER

Constantin Friedrich Röber, Dresden, Germany,
assignor to "Universelle" Cigarettenmaschinen-
fabrik J. C. Mueller & Co., Dresden, Germany

Application August 20, 1935, Serial No. 36,944
In Germany August 27, 1934

8 Claims. (Cl. 131—39)

The present invention relates to means for smoothing the mouth piece ends of cigar fillers, and has for an object to provide a method and apparatus for accomplishing this purpose, so that the mouth piece ends of the fillers when delivered from the press and ready to receive the wrappers will be smooth and even so that the wrappers may be properly applied.

It is well known in the art that cigar fillers with the wrappers thereon are introduced into a press or mold out of which the rolled up ends of the wrapper protrude at opposite sides, particularly at the mouth piece end of the filler. Before the filler is introduced into the press or mold and before the wrapper is applied thereto, the filler is clipped at its ends to remove protruding portions.

In this operation a ridge or projection remains upon the mouth piece end of the cigar and this projection prevents the smooth application of a thin or delicate wrapper. To remove this ridge or projection it is customary to squeeze the clipped end of the filler into a socket having the shape of the cigar point and, by turning, to smooth out the end of the filler and thereby eliminate the ridge.

It has been found in practice that such smoothing out of the ridge on the end of the filler is not satisfactory because it does not absolutely remove the ridge and the same swells or rises from the surface of the cigar point.

To overcome this difficulty is an object of the invention, and means is therefore provided for actually grinding or cutting away this ridge or projection so as to completely remove the ridge and not merely press it back into the body of the cigar.

It is known that means have heretofore been provided for the removal of the compressed edges at the ends of the cigar fillers with the use of a socket receiving the end of the filler to be treated and in which the socket is cut off obliquely to the longitudinal axis of the filler directly in front of a cutting surface such as a rotating wing knife.

However, the cigar filler has to be turned by hand in the socket and the operation is somewhat in the nature of the well known pencil sharpener.

The present invention provides means for overcoming the difficulties encountered with this construction and operation and by so mounting and operating a cutting implement that it will encircle the mouth piece end of the filler and automatically remove the ridge or projection left by the clipping of the wrapper.

With the foregoing and other objects in view,

the invention will be more fully described hereinafter, and will be more particularly pointed out in the claims appended hereto.

In the drawing, wherein like symbols refer to like or corresponding parts throughout the several views,

Figure 1 is a vertical side elevation partly in section of a machine constructed according to the present invention, showing a cigar filler fitted in the socket of the machine at its mouth piece end. 10

Figure 2 is a front view taken axially at right angles to Figure 1, with the bevel gear removed and showing parts in section taken on line 2—2 of Fig. 1, and

Figure 3 is a detail fragmentary view of the mouth piece end of the filler showing in dotted lines the twisted end of the wrapper before clipping and showing a cutter in its relative position thereto.

With reference first to Figure 3, a cigar filler W is shown which has been worked into shape in the usual manner in the shaping press and which shows in full lines the filler after being clipped at its mouth piece end. The rolled up portion of the wrapper, prior to clipping is shown at T and this is the portion which is clipped from the end of the filler. When this portion T is clipped from the filler there remains an annular ridge or projection G which is adapted to be removed by the present invention and by use of a cutter 8. The cigar filler W is held fast while the ridge G is removed. The cutter 8 works against the cigar filler W and is carried around the cigar filler W in the path of the ridge or projection G to remove it by the independent operation of the cutter. 30 This operation may be carried out in various ways and in Figures 1 and 2 there is shown a preferred type of apparatus or device for accomplishing this result.

Referring now to Figures 1 and 2, a drive shaft 1 is connected by gears 2 and 3 to a spindle 4 which is mounted in a suitable bearing 5 of the machine frame. The upper end of the spindle 4 is provided with a socket 6 shaped to the mouth piece end of the cigar filler W. At one side of the vertical axis of the socket 6, the latter is provided with an opening 6a and at one side of the adjacent portion of the spindle 4 is disposed a horizontal shaft 7 which carries a milling cutter 8 the surface portion of which projects into the recess 6a of the socket to an extent sufficient to contact the same for removal of the ridge or projection G. The shaft 7 is mounted in a bracket bearing 9 which rises from the body 10 of the bracket disposed at one side of the spindle 4, and 55

the shaft 7 carries at its outer end a bevel gear wheel 11 which meshes with a second bevel gear wheel 12 carried on the offset vertical shaft 13.

The shaft 13 is mounted in a bearing 14 carried by the body bracket 10. The body bracket 10 is secured to the axle 4 by a pair of spaced ears 15 embracing the shaft 4 and which are adapted to be clamped on the shaft by a set screw 16 or the like as shown.

10 The body bracket 10 thus turns with the shaft about the axis of the latter and carries with it the shafts 13 and 7 so that the milling cutter 8 is maintained at all times in the opening 6a of the socket 6 as the latter turns and smooths the mouth piece end of the cigar filler W.

15 Mounted on the lower end of the offset shaft 13 is a planetary gear wheel or pinion 17 which meshes with a sun gear 18, the latter being supported to turn about the shaft 4 upon a collar 4a or the like, and the sun gear 18 being held against rotation by an anchoring arm 20 secured by a screw 19 or the like to the sun gear 18 and which has an arm extending downwardly and mounted for vertical sliding movement in one side of the 20 main bearing 5 of the machine frame. The spindle 4 is adapted to move vertically in the bearing 5 and the anchoring bracket 20 is adapted to move therewith. The lower end portion of the spindle 4 is provided with a key or spline 21 which 25 engages the hub of the gear 3 so that the spindle 4 may be driven by the gear 3 at all times and the spindle 4 may be slid downwardly through the gear 3.

30 Upon the lower extremity of the spindle 4 is disposed a shifting collar 22 provided with an annular groove 23 for the reception of a fork 24 or other suitable device used in the shifting of shafts or the like so that the collar 22 with the spindle 4 may be moved from the solid to the dotted line 35 position shown in Figure 1. The parts on the upper end of the spindle 4 are moved correspondingly so as to grip the tip or mouth piece end of the cigar filler W.

35 In operation of the machine, the drive shaft 1 turns the spindle and the latter swings the body bracket 10 thereabout while the sun gear 18 remains stationary with the main bearing 5 and consequently the shafts 13 and 7 are rotated so that the milling cutter 8 is turned to trim off the 40 annular projection or ridge G on the mouth piece 45 end of the cigar. The cigar filler W, the cigar filler, is held stationary while the socket 6 slides thereabout and suitably shapes the mouth piece 50 and admits of the removal of the ridge.

55 It is obvious that various changes and modifications may be made in the details of construction and design of the above specifically described embodiment of this invention without departing from the spirit thereof, such changes and modifications 60 being restricted only by the scope of the following claims.

What is claimed is:—

1. A device for removing the annular projection on the mouth piece ends of cigar fillers incident to the clipping of the twisted wrapper end therefrom, comprising a milling cutter, means for supporting the milling cutter against the said annular projection of the cigar filler, and means for moving the milling cutter while turning said cutter around the axis of the cigar filler.

70 2. A device as specified comprising a socket for the reception of a mouth piece end of a cigar filler subsequent to the removal of the twisted wrapper tip therefrom, said socket having a recess in one 75 side, a rotatable milling cutter mounted at one

side of the socket and projecting into said recess to engage the projection on the cigar filler, and means for rotating the socket and the milling cutter about the axis of the socket to bring the milling cutter into contact with all portions of the 5 annular projection on the cigar filler.

3. A device as specified comprising a rotating spindle having a socket on its upper end shaped to the configuration of a cigar mouth piece end and having a recess in one side for registry with the 10 annular projection on a cigar filler incident to the clipping of the twisted wrapper end therefrom, a tangentially disposed bracket mounted on the spindle, gearing mounted on the bracket and including a milling cutter projecting into said recess 15 of the socket for removing the projection from the cigar filler, a stationary sun gear concentric to the spindle, and a planetary gear engaging the sun gear and connected to the gearing of the bracket for operating the milling cutter by rotation of the 20 spindle and bracket.

4. A device as specified comprising a spindle, means for rotating the spindle, a bracket clamped to the spindle and extending tangentially therefrom, a socket on the upper end of the spindle for 25 the reception of the mouth piece end of a cigar filler and having an opening in one side in register with the projection of the filler incident to the clipping of the twisted wrapper end therefrom, a transversely disposed shaft mounted on said 30 bracket, a milling cutter on said shaft projecting into the opening of the socket, a vertical shaft mounted in the outer end of said bracket and connected to said transverse shaft, a sun gear disposed about the spindle and connected to said vertical shaft to turn the shafts and the milling cutter, and anchoring means for the sun gear to hold the latter independently of the rotation of the 35 spindle.

5. In a device as specified, a spindle, driving 40 means for the spindle, a frame bracket slidably supporting the spindle for vertical movement, shifting means on the lower end of the spindle for raising and lowering the same, a socket mounted on the upper end of the spindle adapted when 45 raised to engage the mouth piece end of a cigar filler and having an opening in one side near the bottom thereof and opposite the projection on the cigar filler left upon clipping the twisted wrapper end therefrom, a tangential bracket mounted on the spindle to turn therewith, interconnected 50 shafts mounted on the bracket, a milling cutter mounted on one shaft and projecting into said opening of the socket to remove the projection on the cigar filler, a sun gear mounted upon the 55 spindle, a planetary gear engaging the sun gear and connected to the other of said shafts, and an anchoring bracket carried by the sun gear and slidably engaging the frame bracket to hold the sun gear from turning during rotation of the 60 spindle whereby to operate said shafts and milling cutter to remove the projection from the cigar 65 filler during the turning of the socket thereon.

6. A means for removing the projection on the mouth piece end of a cigar filler comprising a 65 rotatable cutter, means for supporting the cutter for rotation about an axis at right angles to the longitudinal axis of the filler, and means for rotating said supporting means about the longitudinal axis of the filler while simultaneously 70 rotating said cutter.

7. A means for removing the projection on the mouth piece end of a cigar filler comprising a 75 rotatable cutter, means for supporting the cutter for rotation about an axis at right angles to the 80

longitudinal axis of the filler, means for supporting said filler in a position for contact with said cutter, and means for rotating said supporting means about the longitudinal axis of the filler while simultaneously rotating said cutter.

5. A means for removing the projection on the mouth piece end of the cigar filler comprising a rotatable cutter, means for supporting the cutter for rotation about an axis at right angles to the

longitudinal axis of the filler, means for supporting said filler in a position for contact with said cutter, means for shifting said filler supporting means toward or away from said filler, and means for rotating said supporting means about the longitudinal axis of the filler while simultaneously rotating said cutter. 5

CONSTANTIN FRIEDRICH RÖBER.
